UNITED STATES PATENT OFFICE.

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR MARKING SHOE UPPERS.

Application filed September 6, 1919. Serial No. 322,118.

To all whom it may concern:

Be it known that I, LEWIS J. BAZZONI, a citizen of the United States, residing at Swampscott, in the county of Essex and 5 State of Massachusetts, have invented certain Improvements in Machines for Marking Shoe Uppers, of which the following description, in connection with the accompanying drawings, is a specification, like reference 10 characters on the drawings indicating like parts in the several figures.

This invention relates to machines for marking parts such as shoe uppers, and, more particularly, to machines for placing 15 indicating marks upon the material to designate locations for subsequent operations. The invention may be utilized with particular advantage in marking buttonhole locations on shoe upper material and according- 20 ly will be discussed particularly from this viewpoint, although, as to its more general features, it has obviously a broader field of application.

Buttonhole marking machines may be divided into two classes, gang machines, and those in which a single marking tool is used to make a series of marks, the tool and the piece of work presented thereto having relative movement between the making of successive marks. Machines of the latter class, to which the present invention belongs, may be of a much simpler construction than the former and accordingly correspondingly cheaper to manufacture and to maintain in 30 working order. Experience shows that button shoes are fashionable and are manufactured in large quantities comparatively infrequently, only one out of about four or five seasons. Buttonhole marking machines 40 therefore stand idle a large part of the time. A substantial saving in the cost of the machine then becomes important and may well be sufficient to more than overbalance any advantages the gang machines may have.

It is an object of my invention to produce 45 a simple and efficient machine for marking buttonhole locations on the buttonhole flies of shoes in succession as the work is fed forward to a marking tool.

The number and distance apart of buttonholes upon the buttonhole flies of shoes vary 50 greatly with changes of fashion and with different styles and sizes of shoes. It is therefore an object of my invention to pro-

vide satisfactory means for adjusting the machine so that it may make any desired number of equally spaced buttonhole locating marks on the work presented to it, and this quite irrespective of what the length of the fly may actually be, and without the necessity for any computation of the distance between adjacent buttonholes. To accomplish this purpose a feature of the invention lies in the provision of means by which the machine may be operated to divide a line between the locations of the first and last buttonholes into the desired number of equal parts, making an appropriate button-hole-locating mark at each point of division.

In the illustrated embodiment of my invention there is provided a reciprocating work engaging member arranged to feed the work intermittently and a marking member arranged to mark the locations of buttonholes during the intervals in which the work 75 is at rest. A movable member is provided, exemplified as a pointer movable over the work support, and arranged to control the work engaging feeding member so that if the work is placed on the machine, when the marking member is elevated and the feeding member is at its extreme forward position, with the desired location of the first mark under the punch, and with the end of the pointer over the desired location of the last 80 mark, the operation of the machine will divide the intervening distance into that number of equal parts predetermined, as shown, by the form of a cam surface which controls the operation of the feeding member. As 85 the pointer is moved to correspond to the lengths of different pieces of work, the distance apart of consecutive marks is, of course, varied, but the number of marks remains constant. In the illustrated machine, in order to provide for the placing of different numbers of marks on different pieces of work, there is provided a series of interchangeable cam members having different 90 curvatures corresponding to the different 95 numbers of marks desired.

The various novel features of my invention will be fully described in the subjoined specification and particularly pointed out in the following claims.

In the drawings,
Fig. 1 is a perspective view taken from the rear of the machine;

Fig. 2 is a perspective view of a conoidal cam and its related parts, used for the purpose of variably controlling the feed of the work to the marking tool;

5 Fig. 3 is a detail view of the feeding and marking members;

Figs. 4, 5 and 6 are longitudinal sectional views adjacent to the work feeding and marking members, showing different relative positions of these members occurring during the cycle of operation of the machine;

10 Fig. 7 is a perspective view of the feeding and marking members, as viewed from the front of the machine; and

15 Fig. 8 is a diagram of a shoe upper as marked by the machine.

In the embodiment of my invention which I have selected for illustrative purposes, the 20 machine is provided with a base plate 10 from which rise two pairs of standards 12 and 14. Journaled in the latter is a main drive shaft 16 driven from any suitably controlled source of power and having splined 25 thereon, for sliding movement and rotation thereby, a conoidal cam 18. One end of this cam (the left hand as viewed in Fig. 2) is circular and is concentric with shaft 16. The other and larger end is eccentric with 30 respect to the shaft and is substantially oval in form. Two portions of this end, on opposite sides of the shaft, are concentric with the latter and are joined by a smooth curve. The least distance from the periphery of 35 this oval end to the center of the shaft is equal to the radius of the circle at the smaller end. Thus the cam has one portion which lies in the surface of a cylinder and another opposite portion which lies in 40 the surface of a cone.

Bearing against cam 18 is a roll 20 journaled in the end of a lever 22 suitably fulcrumed on a shaft 24 having bearings in standards 14. The other end of lever 22 is 45 connected by a link 26, to a lever 28 fulcrumed at 30 in standards 14. Pivotally mounted on rod 32 supported by standards 12 is a member 34 provided with a removable plate 36 having a cam which is held by a spring 37 against a roll 38 journaled at the 50 end of lever 28. The general form of this cam surface and the means by which it may conveniently be positioned and detachably connected to member 34, as by a screw 39 and a guide or flanges 40, are clearly shown 55 in Figs. 4, 5 and 6. The upper end of the cam surface of plate 36 is conveniently provided with a stop 42 made in the form of a hook to limit the upward movement of roll 60 38 as the conoidal cam permits levers 22 and 28 to move upwardly under the influence of springs 43 which are connected to the lever 22 and to a fixed bar joining the standards 14.

65 At the lower end of pivoted member 34 is

a pawl-like feed member 44 pivoted at 46 and held in work engaging position by a spring 48. This feeding member may conveniently be provided with a small handle 50 by which it may be moved out of work engaging position by the operative while a piece of work is being placed upon the bed of the machine.

70 Mounted at the end of an arm 52 is a marking tool, illustrated as a punch member 75 54, and a presser foot 56 conveniently made in the form of a leaf-spring. The marking tool is moved alternately into and out of work engaging position by means of a cam 58 mounted on and rotated by the main drive 80 shaft 16 and engaging the arm 60, spring held as at 61, and rigidly connected to a suitably journaled rock shaft 62 to which arm 52 is rigidly connected.

85 The bed of the machine may conveniently be provided with an arcuate scale laid off in inches or other convenient units, as illustrated at the right hand end of Fig. 1. Over this scale moves the end of a pointer 64 pivoted at 66 to the bed of the machine and having rigid therewith a pulley 68 around which passes a belt 70 supported by suitable idlers 72 and 74 and connected with a cross head 78 slidably mounted upon rods 79 and provided with a fork engaging a grooved 95 collar 82 on one end of the conoidal cam 18 for sliding the same on drive shaft 16 as the pointer 64 is moved from one position to another. Idler 74 may conveniently be supported by an adjustable member 84 to provide a suitable belt tightener, the member 84 being pivoted to the frame and held at the desired distance therefrom by a screw bolt as shown in Fig. 2.

100 In the operation of the machine, the work, for instance the buttonhole fly of a shoe, is placed on the bed of the machine at that stage in the cycle of operation thereof at which the marking member is in its elevated position and the feed member at its extreme 110 forward position, as illustrated in Fig. 4, with the location at which it is desired to have the first mark directly under the marking tool 54 and with the edge of the work in approximate alinement with the scale on the bed of the machine. This may be facilitated by swinging the feed member upwards by means of its handle 50. Pointer 64 is now adjusted so that its end is directly over the desired location of the last buttonhole. 115 Power is then applied and the work fed step-by-step through the machine. Between steps the punch is lowered through the work. The feeder 44 moves rearwardly and stops, as shown in Fig. 5, the punch holding the 120 work against displacement. The punch thereupon rises, after which the feeder moves forward, taking the work with it, and stops, as shown in Fig. 6, whereupon the punch is again lowered through the 125 130

work. This cycle of operation is repeated the number of times necessary to make the desired number of marks, in accordance with the form of the cam surface on plate 5 36 of pivoted member 34.

It may be noted here that the conoidal cam is provided with two portions running throughout its length having a curvature concentric with the drive shaft so that feeding member 44 will have a short pause at 10 both extremes of its movement, while the marking tool 54 is being moved into and out of work engaging position. During the rearward non-feeding movement of the feeding member 44 the work is held against undesired displacement by the marking tool 54 which has not yet been elevated. The 15 presser foot 56 at all times lightly engages the work, and holds it against upward movement when the marking tool is being withdrawn.

The cam surface of plate 36 is so formed that the feeding movements of member 44 are equal aliquot parts of the distance between the marking tool and the end of the 25 pointer, irrespective of the position of the end of the pointer. Thus if it is desired to mark the location of 12 buttonholes, as illustrated in Fig. 8, there will be 11 equal steps 30 of the feeding member 44 to move the work through the distance between the first and the last mark.

To effectively operate the machine all that is necessary for the operative to know is 35 the desired location of the first and last buttonholes together with the number of button-hole locations to be marked.

The movement of pointer 64 to correspond to the lengths of different pieces of work 40 slides the conoidal cam 18 on its shaft and so varies the amplitude of the oscillations of lever 28 and accordingly of pivoted member 34 and the work feeding member 44. If it is desired to make some other number of 45 marks it is necessary to remove cam 36 and substitute therefor another cam of generally similar form but with its surface so shaped as to move the pivoted member 34 a greater or less distance as the case may be when lever 50 28 is oscillated through a given arc. It is necessary to provide as many of these cam bearing plates 36 as there are different numbers of buttonholes to be marked on the different pieces of work. For this reason the 55 machine is so arranged that these cam bearing plates 36 may be easily and quickly changed so as not to unduly delay the operation of the machine.

Having described my invention, what I 60 claim as new and desire to secure by Letters Patent of the United States is:

1. In a machine of the class described, means for successively marking off equal aliquot parts of a line of selected length on a 65 piece of work, and adjusting mechanism

for said means to vary the length of said parts in proportion to the predetermined length of the line on the different pieces of work to be operated upon.

2. In a buttonhole marking machine, 70 means to make successively a predetermined number of equally spaced marks on a piece of work, and means controllable by the desired locations of the first and last marks to vary the distance apart at which said equally spaced marks are made to accommodate them to the length of the piece of work on which they are to be spaced while maintaining constant the number of said marks.

3. In a machine of the class described, a 80 marking tool; a work support, means for alternately moving said tool into and out of marking relation to a piece of work supported on said work support, means to feed the work forward a step of predetermined 85 length under said marking tool each time said marking tool is moved out of marking relation to the piece of work, and means to vary by infinitesimal increments the length of said steps.

4. In a machine of the class described, a marking tool, a work support, and synchronized means for moving said tool alternately into and out of marking relation to a piece of work supported on said work support and for feeding forward said work with a step-by-step movement constructed and arranged to make a predetermined number of 95 equally spaced marks on said piece of work on a line between any desired location of the 100 first and last buttonholes.

5. In a machine of the class described, a step-by-step operated work engaging means, and mechanism constructed and arranged to operate said work engaging means to feed 105 the work at each step a predetermined aliquot part of a line of any selected length.

6. In a machine of the class described, a step-by-step operated work engaging means, mechanism constructed and arranged to operate said work engaging means to feed the work at each step a predetermined aliquot part of the distance through which the work is to be fed, and means to vary the length of each step so that different pieces of work 115 may be fed any predetermined distance.

7. In a machine of the class described, means to move a piece of work intermittently through equal steps each of which is an aliquot part of the total distance through which the work is to be moved, and means to vary the length of said steps so that a line of any length on another piece of work may be divided into equal aliquot parts.

8. In a buttonhole marking machine, a 125 marking tool, means for feeding work step-by-step thereto, and means for varying the length of the steps of the feed, to accommodate pieces of work of any desired lengths, while maintaining the length of each step at 130

a predetermined fraction of the distance through which the work is to be fed.

9. A buttonhole marking machine comprising a marking tool, means for feeding a piece of work step-by-step thereto, operating means for said marking tool, and means for varying the length of the steps of the feeding means by infinitesimal increments to insure the placing of the last mark at any predetermined point.

10. In a machine of the class described, work feeding means comprising a work engaging feeding member, means to reciprocate said member, and means to vary the length of the reciprocating movements of said member constructed and arranged to maintain the length of said reciprocating movements at a predetermined fraction of the distance through which the work is to be fed, irrespective of what that distance may actually be.

11. In a machine of the class described, a reciprocable work feeding tool, means to reciprocate said tool through a path which is a predetermined fraction of the distance through which the piece of work is to be fed, and means to vary the length of the path of movement of the tool proportionally to the distances through which the different pieces of work to be operated upon are to be fed.

12. In a machine of the class described, means for measuring off a line on a piece of work, and means controlled thereby to divide the line measured off into a predetermined number of equal parts.

13. In a machine of the class described, means for making a number of marks on a piece of work, a member movable over the work in accordance with a desired characteristic of the work, and means controlled thereby to vary the spacing of the marks in accordance with the position of said member.

14. In a machine of the class described, a work support, a member movable thereover in accordance with a desired characteristic of the work, a marking tool, operating means for said marking tool and means controlled by the movement of said member to vary the distance between successive marks made by said marking tool.

15. In a machine of the class described, a work support, a member movable thereover in accordance with a desired characteristic of the work, a step-by-step operated work feeding mechanism, and means operated by the movement of said member to vary the lengths of the steps of the work feeding mechanism in accordance with the position of said member.

16. In a machine of the class described, a work support, a step-by-step operated work feeding mechanism, a pointer movable over said work support, and means operated by the movement of said pointer to vary

the length of the steps of the work feeding mechanism in accordance with the position of the pointer.

17. In a machine of the class described, a work support, a step-by-step operated work feeding mechanism, a pointer movable over said work support, means operated by the movement of said pointer to vary the length of the steps of the work feeding mechanism in accordance with the position of the pointer, and a marking tool constructed and arranged to make a mark on the work each time the work is at rest between the successive steps of its movement.

18. In a machine of the class described, a work support, an intermittently operating marking tool, an oscillating work engaging member arranged to feed the work over the work support to the marking tool, means to oscillate said work engaging member, and a pointer movable over the work support and arranged to vary the amplitude of the oscillations of said work engaging member.

19. In a machine of the class described, a pivoted member, a work engaging and feeding member carried thereby, a lever, means to oscillate said lever and a cam mounted on said pivoted member and projecting into the path of movement of the end of said lever to transmit the oscillation of said lever to said work engaging and feeding member.

20. In a machine of the class described, a pivoted cam-bearing member, a work engaging and feeding member carried thereby, an oscillatable member engaging the cam of said cam-bearing member, said cam being so formed that the length of the path of movement of said work engaging and feeding member is proportional to the amplitude of the oscillation of said oscillatable member, and means for varying the amplitude of the oscillation of said oscillatable member.

21. In a machine of the class described, a drive shaft, a conoidal cam mounted thereon and driven thereby, a reciprocable work feeding member, means operated by said cam to reciprocate said work feeding member, and means to change the relative positions of said cam and said means operated by said cam to thereby change the length of the path through which said work feeding member is reciprocated.

22. In a machine of the class described, a drive shaft, a conoidal cam slidably mounted thereon and rotated thereby and having one end concentric with and the other end eccentric to the shaft, means to slide said cam on said shaft, a reciprocable work feeding member, means operated by said cam to reciprocate said work feeding member in a path the length of which is dependent upon the position of the cam on the drive shaft.

23. In a machine of the class described, a work support, a pointer movable over the work support, a conoidal cam, means to rotate said cam, a reciprocable work feeding member, means operated by the rotation of said cam to reciprocate said work feeding member, and mechanism operated by the movement of said pointer to move said cam endwise relatively to the means operated thereby to vary the length of the path of movement of said work feeding member.

24. In a machine of the class described, a marking tool, a work support, means for alternately moving said tool into and out of marking relation to a piece of work supported on said work support, means to feed the work a step forward under said marking tool each time said marking tool is moved out of marking relation to the piece of work, and means for varying the length of said steps by infinitesimal increments.

25. A buttonhole marking machine comprising a work support, a pointer movable thereover, a marking tool, means for feeding a piece of work step-by-step thereto, operating means for said marking tool, and means operated by the movement of said pointer for varying the length of the steps through which the work is moved by said work feeding means.

26. In a machine of the class described, a main drive shaft, a marking tool, means operated by said drive shaft to move said marking tool into and out of marking relation to a piece of work, a conoidal cam slidably mounted on and rotated by said drive shaft and arranged with some of its elements parallel to said drive shaft, a pivoted cam bearing member, a work engaging and feeding member carried thereby, and a lever oscillated by said conoidal cam and engaging the cam of said cam bearing member to oscillate the latter and thereby to reciprocate said work engaging and feeding member, the length of the work feeding movements of said work engaging and feeding member being dependent upon the amplitude of the oscillation of said lever by said slidable cam.

27. In a machine of the class described, a work support, a pointer movable over the work support, a drive shaft, a marking tool, means operated by the drive shaft to move said marking tool into and out of marking relation to a piece of work on said work support, a conoidal cam slidably mounted on and rotated by said drive shaft and arranged with one end concentric with and the other

end eccentric to said drive shaft, a reciprocable work feeding member, means operated by the rotation of said cam to reciprocate said work feeding member, and mechanism operated by the movement of said pointer to move said cam bodily relatively to the means operated thereby to vary the length of the path of movement of said work feeding member.

28. In a machine of the class described, means to successively punch the holes of a series of holes in a piece of work and means to vary the distance apart at which said holes are punched in proportion to the lengths of the series on different pieces of work while maintaining constant the number of holes in the different series.

29. In a machine of the class described, a work support, a step-by-step operated work feeding mechanism, a pointer movable over said work support, means operated by the movement of said pointer to vary the length of the steps of the work feeding mechanism in accordance with the position of a pointer on the scale, and a tool constructed and arranged to punch a hole in the work each time the work is at rest between successive steps of its movement.

30. A buttonhole marking machine, comprising a marking tool, and means for feeding a piece of work to said tool to receive a series of marks, said feeding means being constructed and arranged to locate the last mark at any selected distance from the first.

31. In a machine of the class described, a marking tool, means for feeding a piece of work to the tool step-by-step to receive a series of equally spaced marks, means for varying the length of the steps to apply the same number of marks to a piece of work of different size, and means for varying still further the length of the steps to place a different number of marks on a piece of work of the same size.

32. In a machine of the class described, a marking tool, means for feeding a piece of work past the tool step-by-step for any predetermined distance to receive a series of equally spaced marks, and means for varying the length of the steps to enable a different number of marks to be spaced equally along the same distance on another piece of work.

In testimony whereof I have signed my name to this specification.

LEWIS J. BAZZONI.
